Primary Examiner — Barbara Fox

(74) Attorney, Agent, or Firm — Banner & Witcoff, Ltd.

CLAIM

The ornamental design for a display screen with icon set, as shown and described.

DESCRIPTION

FIG. 1 is a front view of a display screen with icon set showing our new design; and,

FIG. 2 is a front view of a display screen with icon set showing an alternative embodiment of our new design.

The broken line showing of the remainder of the graphical user interface and display screen is for environmental purposes only and forms no part of the claimed design.
